[57] CLAIM

The ornamental design for a bridge plate for speaker, as shown and described.

DESCRIPTION

FIG. 1 is a perspective view of a bridge plate for speakers embodying my new design;

FIG. 2 is a top plan view thereof;

FIG. 3 is a bottom plan view thereof;

FIG. 4 is a right side elevation view;

FIG. 5 is a left side elevation view;

FIG. 6 is a right end view;

FIG. 7 is a left end view;

FIG. 8 is a reduced top plan view thereof, the edge of an oval speaker being shown in broken lines for illustrative purposes only and forming no part of the claimed design; and,

FIG. 9 is a reduced top plan view thereof, the edge of a circular speaker again being shown in broken lines for illustrative purposes only.
